CLAIM

The ornamental design for the mop bucket, as shown and described.

DESCRIPTION

FIG. 1 is a front perspective view of a mop bucket of the present invention;

FIG. 2 is a front elevational view of the present invention;

FIG. 3 is a rear elevational view of the present invention;

FIG. 4 is a right side elevational view of the present invention;

FIG. 5 is a left side elevational view of the present invention;

FIG. 6 is a top plan view of the present invention;

FIG. 7 is a bottom plan view of the present invention;

FIG. 8 is a front perspective view of the present invention with a handle in an up position; and,

FIG. 9 is a front perspective view of the present invention with a warning sign in a deployed position.

The broken lines shown in all the views are for illustrative purposes only and form no part of the claimed design.
